[57] CLAIM

The ornamental design for the portable light, as shown and described.

DESCRIPTION

FIG. 1 is a front elevational view of a portable light showing our new design;

FIG. 2 is a right side elevational view thereof;

FIG. 3 is a top plan view thereof;

FIG. 4 is a bottom plan view thereof;

FIG. 5 is a rear elevational view thereof; and

FIG. 6 is a top, front perspective view thereof.

The portable light is shaded to indicate contrast.
